UNITED STATES PATENT OFFICE.

DOMINA QUINTAL, OF MONTREAL, QUEBEC, CANADA, ASSIGNOR OF ONE-HALF TO
ROSARIO DÉRY, OF MONTREAL, CANADA.

RAILWAY-SWITCH.

1,355,262.

Specification of Letters Patent.

Patented Oct. 12, 1920.

Application filed November 1, 1919. Serial No. 334,991.

To all whom it may concern:

Be it known that I, DOMINA QUINTAL, motorman, a British subject, residing at 3230^a Letang street, in the city of Montreal, 5 in the Province of Quebec, in the Dominion of Canada, have invented certain new and useful Improvements in Railway-Switches; and I do hereby declare that the following is a full, clear, and exact description of the 10 same.

The present invention relates to improvements in a "railway switch." The main objects of the invention are to provide a simple efficient, durable and economical switch and 15 mechanism which may be readily operated by an approaching car, running in either direction. Another important object is to provide a switch that cannot be clogged by snow, detritus, stones, etc., on account of 20 the vertical operation of the frogs.

In order to more clearly understand the construction and operation of the invention, reference should be made to the accompanying drawings forming part of the present 25 application.

In the drawings:—

Figure 1 is a top plan view of the invention.

Fig. 2 is a side elevation view of the invention with one of the sides of the switch mechanism removed.

Fig. 3 is a side elevation view of the invention, with a casing of the switch mechanism partly broken away; the frogs being 35 shown in a different position as illustrated in Fig. 2.

Fig. 4 is a detailed side elevation of the main frog operating member.

Fig. 5 is a top view of the main frog operating member.

Fig. 6 is a side elevation of the operating cam.

Fig. 7 is a side elevation of a portion of the invention with one of the sides of the casing partly broken away to disclose the operating cam, showing a car truck and switch operating member carried thereby.

Fig. 8 is a perspective view of one of the main lines of the frog.

Fig. 9 is a perspective view of the switch line frog.

Like numerals of reference indicate corresponding parts in each figure.

With reference to the drawings:

1, indicates a casing either formed in

tegrally with or formed separately from, and then secured to a rail section and casing forming together a long narrow box in which is inclosed the switch mechanism. This casing is provided with a plurality of 60 horizontal brackets or supports 2 on which may be provided anti-friction rollers, not shown in the drawings. The rail section is provided with a switch line section 3 each of said sections being provided with the 65 usual wheel grooves 4. At the intersecting point of the switch line section and the main line section, are provided two longitudinal tapered frog holes 5 and 6 respectively which are bored through the bottom of the 70 wheel grooves 4, and communicating with the casing 1. The frog hole 5 is provided in the wheel groove of the switch line section and the frog hole 6 is provided in the wheel groove of the main line section. Adjacent one end of the said main line section is also provided in the wheel groove a longitudinal and elongated hole 7; and 8 is another hole, preferably shorter, provided in the same wheel groove on the opposite side of 80 the frog hole 6.

The casing 1 is preferably enlarged intermediate of its length to form a casing 9 adapted to receive a supplementary switch operating mechanism which will be herein- 85 after described. 10 is the frog operating member which consists of an elongated arm longitudinally disposed in the casing 1 and adapted to be supported and slide to and fro on the brackets 2. A plurality of zig-zag 90 cuts or depressions 11 are provided on the upper edge of said member 10, whereby oblique and supporting lugs 12 are formed. At one end of said member is provided on the upper edge a longitudinal slot 13 in 95 which is pivotally secured the movable gripping element 14 mounted on the pin 15. On the opposite end of the said member 10 is provided a hole 16 in which is secured the pin 17 connecting said member to the lever 18 which is pivotally mounted in the hole 8 on the pin 19 and made to project through said hole when the member 10 is moved in one direction. Intermediate of said member 10 and on one side is also provided a 100 rack 20 which may be made integral with said member or secured thereto. On the opposite side of said member are provided adjacent said zig-zag depression 11, preferably two horizontally projecting pins 21. 110

The function of the lugs 12, rack 20, gripping element 14 and pins 21 will be explained hereinafter. In the tapered hole 6 provided in the wheel groove of the main rail section is adapted a correspondingly tapered frog element 22 which movably fits in said hole and is provided with a horizontally and longitudinally extending shoulder 23 which is adapted to rest under 10 the top of the casing 1 and prevents further upward movement of the frog element. On the under edge of said element are provided zig-zag depressions 24 forming downwardly projecting lugs 25 adapted to interlock in 15 the zig-zag depressions 11 and lugs 12 provided on the upper edge of the frog operating member 10. These lugs and depressions are so that when the said member 10 is moved on longitudinally, the frog 22 will 20 be made to ascend or descend through the hole 6.

The lugs 12 on the operating member 10 are so adapted that they will engage the depressions 24 on the frog element 22 when 25 the said frog is in its lowermost position. When the operating member 10 is moved horizontally the lugs 12 and 25 will come one above the other and thereby form a solid rest thus preventing the fall of the frog. 30 This is a most important feature of the present invention as the frog will be securely locked in its upper position and can be unlocked only by a horizontal movement of the operating member 10. The frog element 22 is also provided at one end thereof with 35 a slot 26 adapted to receive the apex of the angle formed at the intersection of the main and switch section. The opposite end of said frog element 22 is curved to form an 40 abutment 27 which is adapted to rest against a cross wall 28 provided in the casing, when it is in its lowermost position. Adjacent said frog 22 is movably disposed in the frog hole 5 the switch frog element 29 which is 45 also tapered to fit easily in said hole, said frog being provided with a plurality of depressions 30 adapted to form hook-shaped recesses 31. 32 are pawls pivotally secured in one of the walls of the casing 1 and so 50 disposed as to engage at their upper ends the recesses 31 and at their lower ends they are pivotally mounted on the pins 21 provided on the operating member 10. It will readily be seen that on moving the member 55 10 in one direction, the pawls 32 will be tilted in the opposite direction, so that when the main frog 22 is moved upwardly simultaneously the switch frog 29 will be moved downwardly. Naturally when the frog 29 60 is in its uppermost or operative position it will be locked and held rigid in this position unless the operating member 10 is moved horizontally. The switch frog element is also provided with an abutting end

33 which is adapted to rest against the cross 65 wall 28 in the casing 1.

The main and switch frogs are operated in two preferred ways as disclosed in the drawings. One way is practically automatic while the other way is somewhat similar, to that now employed, that is by means of a key which may be inserted in a key hole 34 provided at the end of the stub shaft 35 which is vertically journaled in the bottom and top of the casing 9 forming part 70 of the main casing 1. On this stub shaft 35 is mounted a toothed quadrant 36 which is adapted to engage the rack 20 on the operating member 10. It is evident that by turning the stub shaft 35 by means of the key, the 75 said member 10 will be moved one way or the other, thus operating the frogs. This apparatus and method should be used if desired in emergency cases.

The member 10 controlling the vertically 80 movable switch sections 22 and 29 is preferably automatically operated by the following mechanism: In a suitable channel in the walls of the casing 1 is provided a cam member 37 shown in Fig. 6. This member 85 37 comprises a spiral thread 39 adapted to project upwardly through the opening or hole 7 provided in the wheel groove of the rail to be acted upon by an approaching car or train as will be hereinafter described. 90 The cam 37 is provided with a pair of cams 38 adapted to engage the gripping member 14 pivoted to the controlling member 10 which are so related to the opposite sides of the gripping member 14 that they may engage either one or the other of the sides of the member 14. For instance as shown in 95 Fig. 2, the cam 38 to the right of the rod is in position to engage the right-hand side of the lever 14; and, if the cam member 37 100 is rotated at this time, the right-hand side of the lever 14 will be depressed moving the left-hand side up into position to be engaged by a cam 41 provided on the cam member 37. The continued rotation of the 105 cam member 37 will cause this cam 41 to engage the left-hand side of the lever 14 and by means of the latter moves the controlling member 10 to the right to the position shown in Fig. 3. If the member 37 is again rotated 110 while the controlling member 10 is in the position shown in Fig. 3 the cam member 38 on the left-hand side will raise the right-hand side of the lever 14 into position to be engaged by a cam 40 at the right. The 115 continued rotation of the member 37 will cause, by the engagement of the cam 40 with the right hand side of the lever 14, a movement of a controlling member 10 toward the left and thus change the relation 120 of the switch sections. It will be seen therefore that the controlling member 10 will 125 always be moved from the position it occu-

pies to the other position at each single rotation of the controlling member 37.

The eccentric roller member 37 is preferably operated by means of the trip or hook 5 carried by the car truck illustrated in figure

7 of the drawings and comprises an arm 42 pivotally secured to any suitable part of the truck frame, and slightly bent and provided at one end with a rather narrow grip adapted to engage the spiral thread 39 which projects through the hole 7. The gripping end of said trip preferably slides in the wheel groove when it is dropped to operate the eccentric roller member. At the other end of 15 said trip 42 is provided a spring 43 which is secured to the truck frame whereby the said trip will be made to keep in close contact with the wheel groove. Adjacent the gripping end of the trip is secured an operating cord 44 which passes over convenient pulleys and projects through the flooring of the car close to the motorman, the said cord 44 being adapted to be operated by a hand lever 45.

25 It is obvious that when member 10 is moved horizontally and one of the frogs is moved in position, the lever 18 will be simultaneously operated. The object of this lever is to provide means of moving back 30 into the nonoperative position the frog element 22 if a car comes on the opposite position on the main line. When the frog 22 is in its lowermost position, the lever 18 is also down, as disclosed in Fig. 2 of the 35 drawings.

The track sections are locked against movement relatively to one another except by the movement of the controlling member 10 by the particular cam formation of the 40 projections 12 and 25 so that the track sections cannot be moved except by operation of the pinion 36 through the socket 34 or by the rotation of the cam member 37.

The operation of the invention is obvious 45 from the foregoing description and it must be understood that changes may be made in the construction, arrangement and disposition of the different parts of the invention and it is meant to include all such in this 50 application, in which only a preferred form has been disclosed.

What I claim as my invention is:—

1. In a railway switch, the combination of 55 a frame including main and side track section; a switch section mounted in said frame for vertical movement to and from operative position; automatically operated mechanism for causing said switch section to be moved to operative position, said mechanism comprising arms pivoted in said frame and connected to the switch section to move the same to and from operative position; another switch section mounted in said frame for vertical movement to and from operative 60 position; and camming means associated

with the automatically operated mechanism for causing the last named switch section to be moved in a vertical plane in direction opposite to the direction of the first named switch section.

2. In a railway switch, the combination of 70 a frame including main and side track sections; a switch section associated with each of said sections; and automatically operated means for raising one of said switch sections 75 to operative position while lowering the other switch section to inoperative position, said mechanism comprising pivoted arms connected to one of said switch sections and camming means engaging the other of said 80 switch sections.

3. In a railway switch, the combination of 85 a frame including main and side track sections; a switch section associated with each of said sections and mounted in said frame for independent movement in a vertical plane; and automatically operated means for raising one of said switch sections to 90 operative position while lowering the other switch section to inoperative position, said 95 mechanism comprising pivoted arms connected to one of said switch sections and camming means engaging the other of said switch sections.

4. In a railway switch, the combination of 95 a frame including main and side track sections; a switch section associated with each of said sections and mounted in said frame for independent movement in a vertical plane; a reciprocating operating member 100 mounted in said frame; bell cranks mounted in said frame and connecting the reciprocating member to one of said switch sections; cams on said reciprocating member adapted to control the other of said switch sections; gear teeth on said reciprocating member; and a pinion mounted in said frame and adapted to operate said reciprocating member 105 to move either of said switch sections to operative position while moving the other 110 of said switch sections to inoperative position.

5. In a railway switch, the combination of 115 a frame including main and side track sections; a switch section associated with each of said sections and mounted in said frame for independent movement in a vertical plane; a reciprocating operating member mounted in said frame; bell cranks mounted in said frame and connecting the reciprocating member to one of said switch sections; cams on said reciprocating member adapted to control the other of said switch sections; gear teeth on said reciprocating member; a pinion mounted in said frame and adapted 120 to operate said reciprocating member to move either of said switch sections to operative position while moving the other of said switch sections to inoperative position; lugs mounted on said reciprocating member 125 130

ber; and a rotatable camming member adapted to engage said lugs and operate said reciprocatory member.

6. In a railway switch, the combination 5 of a frame including main and side track sections; a switch section associated with each of said sections and mounted in said frame for independent movement in a vertical plane; a reciprocatory operating member mounted in said frame; bell cranks mounted in said frame and connecting the reciprocatory member to one of said switch sections; cams on said reciprocatory member adapted to control the other of said 10 switch sections; gear teeth on said reciprocatory member; a pinion mounted in said frame and adapted to operate said reciprocatory member to move either of said switch sections to operative position while moving the other of said switch sections to inoperative 15 position; lugs mounted on said reciprocatory member; a rotatable camming member adapted to engage said lugs and operate said reciprocatory member; and means on 20 said rotatable camming member adapted to be engaged by a member on an approaching car for rotating said rotatable member.

7. In a railway switch, the combination of 30 a frame including main and side track sections; a switch section associated with each of said sections; automatically operated means provided in advance of said switch sections for raising one of the said switch sections to operative position while lowering 35 the other switch section to inoperative position, said means being operable by an approaching car and comprising pivoted arms connected to one of said switch sections; camming means engaging the other of 40 said switch sections; and means located at the other side of said switch sections for rendering one of said switch sections inoperative, said last named means being operable

by a car approaching the switch from the opposite direction.

8. In a railway switch, the combination 45 of a frame including main and side track sections; a switch section associated with each of said sections and mounted in said frame for independent movement in a vertical plane; a reciprocatory operating member mounted in said frame; bell cranks mounted in said frame and connecting the reciprocatory member to one of said switch sections; cams on said reciprocatory member 50 adapted to control the other of said switch sections; lugs mounted on said reciprocatory member; and a rotatable camming member 55 adapted to engage said lugs and operate said reciprocatory member.

9. In a railway switch, the combination 60 of a frame including main and side track sections; a switch section associated with each of said sections and mounted in said frame for independent movement in a vertical plane; a reciprocatory operating member mounted in said frame; bell cranks mounted in said frame and connecting the reciprocatory member to one of said switch sections; cams on said reciprocatory member 65 adapted to control the other of said switch sections; lugs mounted on said reciprocatory member; a rotatable camming member 70 adapted to engage said lugs and operate said reciprocatory member; and means on said rotatable camming member 75 adapted to be engaged by a member on an approaching car for rotating said rotatable member.

Signed at Montreal, Quebec, Canada, this 80
25th day of September, 1919.

DOMINA QUINTAL.
